UNITED STATES PATENT OFFICE.

EMILE GIRARDEAU, OF PARIS, FRANCE.

PROTECTIVE APPARATUS FOR RADIOTELEGRAPHIC STATIONS.

1,035,958.

Specification of Letters Patent. Patented Aug. 20, 1912.

Application filed May 26, 1911. Serial No. 629,686.

To all whom it may concern:

Be it known that I, EMILE GIRARDEAU, a citizen of the Republic of France, residing at 128 Rue de la Boetie, Paris, in the Republic of France, have invented certain new and useful Improvements in Protective Apparatus for Radiotelegraphic Stations, of which the following is a specification.

With the object of increasing the rapidity 10 of the operation between the transmitting and receiving apparatus in radio-telegraphic stations the following method of mounting has already been employed (Figure 1); assuming for the sake of clearness that the 15 antenna A is excited indirectly by means of a Tesla transformer P S and is connected to earth by the intermediary of a gap C from the terminals of which the primary of the reception jigger J is branched, its secondary 20 circuit being closed upon the detector D. In these conditions if the transmitting apparatus does not work and if the electro-magnetic waves coming from an operative station excite the antenna A the gap C does 25 not permit of the direct passage of the current then circulating between this antenna and the earth and this current being obliged to circulate in the primary of the jigger J the signals emitted from the transmitting 30 station are recorded by the detector D. If, on the other hand, the station is rendered operative by means of the oscillating circuit containing the spark gap E and the primary P of the Tesla transformer and if the spark- 35 ing distance in C is sufficiently small a spark is struck between the electrodes of this gap and short circuits the primary of the jigger at the terminals of which the tension cannot 40 in any case exceed the value corresponding to the sparking distance in C. This distance, cannot, however, be reduced beyond a certain value without setting up a permanent short circuit in C, for example, owing to a 45 deposit produced by the passage of the spark, a deformation of the electrodes and so forth. It follows that the detector D should be relatively strong, that is to say, in general not very sensitive as it should not 50 be injured when a tensioning of the nature of the magnitude of the sparking tension of the break is applied to the terminals of the primary of the jigger J. The arrangement contemplated by the present invention 55 obviates this defect and renders it possible to employ sensitive detectors.

Figs. 1 and 2 of the accompanying draw-

ing represent two diagrams of my improved arrangement.

From the labors of H. Hertz and other experimenters it is known that the explosive potential of a spark gap is lowered considerably by the action of ultra-violet light. This ultra-violet light can be furnished by an oscillating spark, a vacuum tube and so forth. Accordingly if the break C is located (Fig. 1) in proximity to the spark gap E itself of the primary oscillating emission circuit when this gap becomes operative it automatically lowers the explosive potential in C and consequently largely reduces the strain on the detector D. Instead of utilizing the influence of the gap E directly a vacuum tube or a neon tube T (Fig. 2) can be employed (for example being branched either off the extremities of a portion of the primary circuit or of the secondary circuit or even off the terminals of the gap E and so on. Obviously the illumination of this tube during the operation of the emission system produces the desired effect.

It will be obvious that numerous modifications may be devised without altering the principle of the invention; when the method of mounting illustrated in Fig. 2 is employed for example the tube T can be furnished with a tension limiting device.

What I claim and desire to secure by Letters Patent of the United States is:—

1. In a radio-telegraph station, a receiving apparatus, a transmitting apparatus, a device including a spark gap for protecting the receiving apparatus from the waves radiating from the transmitting apparatus, and means for generating ultra-violet rays 90 of light in proximity to the spark gap.

2. A receiving apparatus in a radio-telegraph system including means for detecting waves from a distant station, a device including a spark gap for protecting said apparatus from the waves transmitted at its own station, and means generating and utilizing the action of ultra-violet rays of light upon said spark gap.

3. In a radio-telegraph system a receiving apparatus, a transmitting apparatus including a spark gap, means including a spark-gap for protecting said receiving apparatus from the waves of said transmitting apparatus disposed with said spark gap in 105 such proximity to the spark gap of the transmitting apparatus that the spark gap

of the protecting means is subject to the action of the ultra-violet rays generated by the spark gap of the transmitting apparatus.

5. 4. In a radio-telegraph system, a receiving apparatus, a transmitting apparatus, a device including a spark gap for protecting said receiving apparatus from the waves generated by said transmitting apparatus,

and means whereby said transmitting apparatus generates ultra-violet rays of light in proximity to said spark gap.

In testimony whereof I affix my signature in presence of two witnesses.

EMILE GIRARDEAU.
